SHOE AND OUTSOLE THEREFOR

William Mackensen, New York, N. Y., assignor
to Industrial Exploitation Corporation, Long
Island City, N. Y., a corporation of New York

Application January 27, 1943, Serial No. 473,667

7 Claims. (Cl. 36—19.5)

This invention relates to shoes and more particularly to shoes in which the outsole is secured to the upper by means of an adhesive, such shoes being known as cemented shoes.

In the manufacture of cemented shoes as heretofore practiced, the adhesive is applied both to the upper surface of the outsole and to the surfaces of the upper and of the insole to which the upper surface of the outsole is secured. Usually the adhesive which has been applied to said surfaces is in dry condition prior to the assembly of the outsole with the upper and insole, so that it is necessary to soften the adhesive, usually by means of a solvent applied to the adhesive, just before the outsole is assembled with the upper and insole.

One object of the present invention is to eliminate the application of adhesive to the upper and insole as heretofore required in the manufacture of cemented shoes, thus effecting a substantial reduction in the quantity of adhesive, as well as effecting a substantial reduction in the quantity of solvent, required for securing the outsole in the shoe, and also saving time, labor, and power, and simplifying the manufacturing operations and improving the comfort of the shoe on the wearer.

Another object of the invention is the provision of a cemented shoe in which the bond between the outsole and the upper and insole is greatly improved.

A further object is to provide a prepared outsole which can be easily secured to the upper and insole in accordance with the principles of this invention.

The above and other objects of the invention will be fully understood from the following description, reference being had to the accompanying illustrative drawing.

In the drawing:

Fig. 1 is a perspective view of a shoe embodying the present invention;

Fig. 2 is a transverse sectional view on the line 2—2 of Fig. 1;

Fig. 3 is a top perspective view of the outsole;

Fig. 4 is a sectional view of the outsole on the line 4—4 of Fig. 3.

Referring now to the drawing in detail, the invention is illustrated as applied to a cemented shoe made in accordance with the general principles of the Sbicca method of making cemented shoes, as described in United States Patent No. 1,838,708, but it will be understood that my invention applies to all other types of cemented shoes.

The shoe 10 embodying the present invention, being herein shown as a cemented shoe of the Sbicca type, comprises an outsole 12 having a raised projection 13 in the forward portion thereof of which fits within the opening 14 in the forward part of the insole 16, the upper marginal surface of the outsole around said projection being adhesively secured to the lasting allowance of the upper 18 and to the bottom surface of the insole-rand part 20 which surrounds opening 14, and the rest of the upper surface of the outsole being adhesively secured to the lasting allowance of the upper and to the bottom surface of the insole from the rear edge of opening 14 to the back of the shoe. It will be understood that the inner surface of the lasting allowance of the upper is adhesively secured to said insole. In accordance with the present invention, it is unnecessary to apply cement or other adhesive to the lower surface of the lasting allowance of the upper or to the lower surface of the insole rearwardly of the rear edge of insole opening 14.

Referring now more particularly to the outsole 12, the latter is prepared in the manner which will now be described for accomplishing the objects of the invention. The upper surface of the leather sole blank, except the upper surface of projection 13, is roughened and a coating 22 of cement, usually a pyroxylin adhesive, is applied to said roughened surface, a narrow trimming edge 24 being left without adhesive. Then while the adhesive is still moist or soft and tacky, a layer 26 of felt or other suitable fibres in dry condition is applied to said cement coated surface. Preferably in applying the fibres to the outsole, said fibres are blown onto the adhesive coated surface, but it will be understood that said layer of fibres may be applied in any other suitable way. Then a thin coating 28 of cement, usually a pyroxylin adhesive, is applied to the layer of fibres, whereby the felt fibres are coated with adhesive and secured in the layer. Thereafter, usually after the cement has dried, the layer of fibres is provided with a plurality of indentations or shallow pits 30 disposed preferably substantially throughout the upper surface of said felt layer. The provision of these indentations is preferred as they are believed to contribute to the improved securement of the outsole in the shoe, but it will be understood that it is within the scope of this invention to omit them. After the outsole is thus prepared it is ready for securement to the upper and insole.

Ordinarily, the cement applied to the fibrous layer 26 is hard or dry at the time the outsole

is applied to the upper and insole. Accordingly, at the time the outsole is to be attached, a solvent for the cement is applied over layer 26 rendering the cement soft and tacky. Then, while the cement is soft and tacky, the outsole is applied and the shoe placed in a press for holding the outsole in position under pressure while the cement sets. The shoes are allowed to remain in the press until the soles are securely adhered to the insole and to the lasting allowance of the upper. The period of pressure application is usually about fifteen minutes and after about two hours of drying, the soles are ready for levelling. Then the soles and the shoes may be finished in the usual way. The heel-breast covering flap 15 of the outsole is indicated at 32.

While I have shown and described the preferred embodiment of my invention, it will be understood that the latter may be embodied otherwise than as herein shown or described and that in the illustrated embodiment certain changes may be made. Accordingly, I do not wish to be limited to the invention as herein specifically illustrated or described except to the extent which may be required by the scope of the appended claims.

Having thus described my invention, what I claim and desire to secure by Letters Patent is:

1. In a cemented shoe having an upper, an insole, and an outsole, said outsole comprising a leather sole blank having a layer of fibres adhesively secured to the upper surface thereof, and a coating of adhesive on the upper surface of said layer of fibres, said layer of adhesive coated fibres having a plurality of indentations in the upper surface thereof, said outsole blank being secured to said insole and to the lasting allowance of said upper by said layer of fibres and said adhesive.

2. A prepared outsole for a cemented shoe, said outsole comprising a leather sole blank having a layer of fibres adhesively secured to the upper surface thereof, and a coating of adhesive on the upper surface of said layer of fibres, said layer of adhesive coated fibres having a plurality of indentations in the upper surface thereof.

3. The method of preparing a leather outsole for a cemented shoe, which comprises roughening the upper surface of a leather outsole blank,

applying a coating of adhesive to said surface, placing a layer of fibres on said adhesive coating while it is moist, and then coating said fibres with an adhesive, and forming a plurality of indentations in the upper surface of said layer of fibres.

4. In a cemented shoe having an upper, an insole having an opening in its forward part, and an outsole provided with a projection which fits into said opening, the inner surface of the lasting allowance of said upper being secured to said insole, means securing said outsole to said insole and to the outer surface of the lasting allowance of said upper, said means comprising a layer of fibres on the upper surface of said outsole adhesively secured to said surface of the outsole and to the outer surfaces of the said insole and lasting allowance of the upper.

5. In a cemented shoe having an upper, an insole, and a leather outsole, means securing said outsole to said insole and to the outer surface of the lasting allowance of said upper, said means comprising a layer of felt fibres on the upper surface of said leather outsole adhesively secured to said surface of the outsole and to the outer surfaces of the said insole and lasting allowance of the upper, said layer of adhesive coated fibres having a plurality of indentations in the upper surface thereof.

6. In a cemented shoe having an upper, an insole, and a leather outsole, a fibrous layer interposed between the upper surface of said leather outsole and the adjacent surface of the lasting allowance of the upper and between the upper surface of the outsole and the lower surface of the insole and adhesively secured to said surfaces and thereby securing said outsole to said insole and to the upper, said fibrous coated layer having a plurality of indentations in the upper surface thereof.

7. A prepared outsole for a cemented shoe, said outsole comprising a leather sole blank having a central raised forward portion and an upper surface below the upper surface of said raised portion, and a fibrous layer adhesively secured to said first mentioned upper surface and having a coating of cement thereon for adhesively securing the outsole to the upper of the shoe.

WILLIAM MACKENSEN.
